ASSIGNORS TO AUTOMOTIVE MAINTENANCE MACHINERY CO., OF CHICAGO,
ILLINOIS, A CORPORATION OF ILLINOIS

CYLINDER GRINDING TOOL

Application filed April 9, 1930. Serial No. 442,731.

Our invention relates generally to cylinder-grinding tools of a character well adapted to bring the surface of the cylinder to true cylindricity, accurate diameter and smooth finish, and has to do particularly with so-called "dry grinding" tools of this character.

In the grinding of cylinders with abrasive tools, two methods have been employed; namely, wet grinding and dry grinding. In 10 wet grinding, the grinding tool is rotated, or otherwise moved, in contact with the cylinder wall surface and during this operation a lubricant (such as kerosene, or the like) is flowed on to the tool for reasons which will 15 be well understood by those skilled in the art. This method has its advantages in that there is no flying abrasive dust and sufficient lubrication is provided for smooth operation and the desired finish. However, it also has its 20 disadvantages, among which are the necessity of providing for the flow of the lubricant upon the tool in the cylinder, and a so-called abrasive soup is formed which must be kept away from the parts (valves, bearings, electric parts, etc.) of the motor. Also, in the 25 use of tools of this character for surfacing worn cylinders it is quite inconvenient for the operator to be required to handle, adjust the flow of, feed, etc. the lubricant to the tool 30 during operation.

In dry grinding with a tool of the foregoing character, the tool has been operated dry and without any lubricant. The advantages of this method are the simplicity and facility 35 in operation, fast cutting speed and the elimination of abrasive "soup". However, the dry grinding methods heretofore employed have involved several disadvantages, among which are rough finish due to lack of lubricant and the formation and discharge of a 40 cloud of abrasive dust during operation. This dust settles upon the working parts of the motor, upon the working parts of the tool and upon nearby machines with obvious 45 harmful effects, and it is also seriously injurious to the lungs of the operator.

One of the main objects of our invention is to provide a tool of the foregoing character 50 which embodies all of the advantages of both the prior wet and dry grinding methods, but

which has none of the disadvantages thereof. Another object is to provide a simple and inexpensive tool of the foregoing character which is capable of fast grinding with high efficiency, and which is quite economical in 55 use with a consequent reduction in cost of the cylinder grinding operation. Our invention further provides a tool which is light in weight and easy to handle and which is capable of use over long periods of time with 60 a high degree of accuracy in performance; and it provides a tool which requires a minimum of attention on the part of the operator.

A further object is to provide a cylinder 65 grinding tool which operates with the required smoothness and which produces the high quality of finish without the use of a so-called wet lubricant.

An additional object is to provide a cylinder 70 grinding tool which embodies abrasive and guide elements so treated with a semi-solid lubricant that in operation the desired lubricating effect is accomplished with dry 75 grinding advantages, the arrangement being such that the abrasive dust is loaded or weighted down with the lubricant medium to such an extent that it falls downward through the cylinder bore (instead of being freed as dry dust) where it may be readily 80 caught and disposed of.

A more specific object of our invention is to provide a dry grinding type of cylinder 85 grinding tool which embodies abrasive elements and guides formed of felt, or similar material, simultaneously expandible and contractible toward and away from the cylinder wall surface, the guides, particularly, (and in certain instances, the abrasive elements also) being impregnated with a semi-solid lubricant which may be applied to the cylinder 90 wall surface by contact of the guides with such surface. One such lubricant may take the form of tallow, paraffin, or similar material which assumes a semi-solid condition when cooled, combined with graphite 95 for the purpose of increasing the lubricating qualities of the medium.

A further object is to provide a tool of the foregoing character wherein the felt material is impregnated with a lubricating medium of 100

a character adapted to strengthen and stiffen the felt body sufficiently to support it against free resiliency during the grinding operation.

5 Other objects and advantages will become apparent as this description progresses and by reference to the drawing which shows one form of the tool embodying our invention.

In the drawing,

10 Figure 1 is a vertical sectional view of the tool with a portion thereof shown in elevation; and

Fig. 2 is a horizontal section taken substantially on line 2-2 of Fig. 1.

15 Referring particularly to the tool shown in the drawing, it embodies a frame or body of cage-like construction comprising end plates 10 and 11 rigidly secured together in spaced relation by a plurality of tie bars 12.

20 The tie bars, in this particular form of tool, are sufficient in number and are so arranged that there is provided a center space 13 with four radial passages 14 leading therefrom, each of the latter being adapted to receive 25 abrasive or guide carriers 15, as the case may be. It will be understood that while I have shown my invention as applied to a tool of the foregoing character it is equally applicable to tools employing any desired number of 30 abrasive and/or guide carriers.

The carriers 15 are mounted in the passages 14 in such a manner that they are expandable and contractible for varying the working diameter of the tool. Each carrier 35 consists of a body 16 having a head 17 on its outer edge which is greater in thickness than the body. The head of each carrier is channeled as at 18 to detachably receive and support in any desired manner, an abrading 40 stone, or similar element, 18, or a guide element 19. Sole guidance and support for the carriers 15 is provided by the end plates 10, 11 as follows: Each end plate is provided with guide grooves 20 which extend in radial 45 direction substantially from the centers of the plates (or tool axis) to the outer edges thereof, providing long and deep supporting surfaces. The body of each of the carriers is of greater length than the distance between 50 the end plates providing projecting tongues 16 at the ends of the bodies which are of suitable size to fit snugly, but slidably, in the end plate grooves 20.

The carriers are expanded and contracted 55 in the following manner: The body of each carrier is of sufficient depth for its inner edge to extend into the center space 13 of the cage frame, and inclined surfaces 25, 26 are provided on such inner edges for co-action with 60 adjustable wedging means movable axially of the tool to control the working diameter thereof. By such an arrangement, all of the carriers are adjusted simultaneously and to similar extents with respect to the tool 65 axis. The adjusting means consists of a

center stem 21 rotatably mounted on the axis of the tool and screw threaded at 22 to adjustably receive two wedged-members or cones 23, 24 of identical taper which cones engage the correspondingly inclined carrier body surfaces 25, 26. Rotation of the cones 23, 24 is prevented, during the rotation of the adjusting stem 21, by means of a rod 27 carried by the end plates 10, 11 and engaging a groove 28 in each of the cones. The cones are, preferably, arranged in tandem with their small ends upward so that upon actuation of the center stem 21 to move the cones 23, 24 to expand the carriers, such cones also wedge the carrier body ends in the end plate 70 grooves, thereby providing a strong, durable and rigid-type tool. The carriers are held pressed inwardly against the cones 23, 24 by means of spring rings 29 which engage suitable grooves in the opposite ends of the carrier bodies. 75

In the particular form of tool shown in the drawing, it will be noted that, while the carrier bodies are mounted substantially parallel with the tool radius, they are each so located that the median line thereof is offset rearwardly (with respect to direction of rotation—Fig. 2—rotation clockwise) from the tool radius; and, further, the abrasive and guide elements 18, 19 are so located that their median lines are offset rearwardly from the median line of the carrier bodies. With this arrangement, any tendency of the carriers to rock during the grinding operation will result in a relief in abrading pressure. Although I have shown the carriers mounted in the foregoing manner, it will be understood that such carriers and the abrasive elements and guides may all be mounted directly on the tool radius, or the median line of the carrier body may be located rearwardly of the tool radius with the median line of the abrasive elements and guides located on the median line of the carrier body. 90 95

Movement of the center stem 21 to adjust 100 the cones 23, 24 is accomplished by means of a rotatably mounted adjusting dial 30 secured to the outwardly disposed end of the adjusting stem which projects through the upper end plate 10. This end plate 10 is provided on its upper side with a recess 31 which receives and confines a flat disk-shaped spring 32 through which the center stem 21 passes. A sleeve 33 is disposed between the spring 32 and the underside of the dial 30 105 in such a way that in the assembled position of these parts the spring 32 is under slight compression. A cage-like drive head 34 is mounted upon the end plate 10 by means of screws 35 engaging suitable openings in the end plate 10 and the head skirt 34. The drive head is provided with a parti-spherical end 36 which is provided with a cross pin 36 for bayonet-lock engagement with a suitable driving medium (not shown). The 110 115 120 125 130

cage-like construction of the head 34 provides for ready access to the dial 30 for adjustment of the center stem 21 and carriers 15. With the construction just described, the 5 adjusting dial 30, stem 21 and cones are tensionally positioned as a unit, thereby tending during operation to hold the grinding stones in abrading contact with the cylinder wall surface under a continued grinding pressure 10 throughout any particular adjustment setting, resulting in a more rapid grinding operation.

The tool structure so far described is well adapted for dry grinding and my invention 15 has to do mainly with the adapting of the same, as well as various other forms of cylinder grinding tools, for dry grinding operations in such a way as to attain the advantages of both wet grinding and dry grinding, but 20 with none of the disadvantages thereof.

In dry grinding tools heretofore employed, it has been customary to utilize two opposed carriers to support abrasive or grinding elements, and two additional and opposed carriers 25 supporting guide elements (which have no material abrading effect) to properly position the tool with respect to the cylinder wall surface so that the desired cylindrical finish will be obtained. In attempts heretofore made in this direction, the guides have 30 been formed of wood, cotton, belting, fibre and other similar materials. These prior used materials are objectionable for the reason, among others, that they do not wear 35 away proportionately to the wear in the abrasive element. In tools of a character wherein the carriers are adjustable simultaneously to similar extents, this differential in wear prevents accurate simultaneous adjustment of 40 the guides and stones to effect proper grinding and guiding contact with the cylinder wall surface, whereby in operating such prior forms of tool it has been necessary to frequently remove the same from the cylinder 45 and dress the guides and abrasive surfaces to approximately the same projection before the tool will operate properly. Our invention eliminates this objectionable condition in addition to providing for the attainment 50 of the advantages hereinbefore mentioned.

Specifically, we have found that these differential wear conditions can be eliminated by the use of a felt, or similar, material for the guide elements, and by shaping the guide 55 elements similarly to the abrasive elements. Extensive tests and experimentation have definitely shown that material of this character has the ability to wear in substantially the same proportion as the abrading elements 60 which are customarily used.

Attainment of the advantages of both the wet grinding and dry grinding methods is provided for as follows: The felt material is 65 impregnated with a lubricating medium or compound, under conditions to be explained

hereinafter, which when cooled tends to set and harden. The felt has the ability to retain intimately therein the semi-hardened lubricant medium without loss of the same due to centrifugal, or other, action set up in the 70 movement of the tool in the cylinder.

A preferable lubricant compound which we have found to satisfactorily serve our purpose in the foregoing regard is tallow or paraffin, or like material, and graphite. Tallow 75 and paraffin have lubricating qualities, and in a cooled state assume a semi-solid condition. Upon being heated, they become sufficiently fluid to readily penetrate the felt material and saturate the same. Tallow or paraffin or similar material, may be used alone as the lubricating agent for the felt; but for best results we prefer to add graphite thereto for increased lubricating qualities. The graphite is added to the hot fluid-form tallow or 80 paraffin in that quantity which the fluid-like paraffin or tallow will hold in suspension. The felt may be saturated or impregnated with the hot fluid-form compound by immersing the felt therein in any desired manner, or 85 the felt material may be impregnated with this medium in any other suitable manner without departing from our invention. After this treatment the felt material is allowed to cool so that the medium therein will assume 90 a semi-solid state. Our invention also contemplates similar treatment for the abrasive elements, although the abrasive element may not be capable of impregnation to the same extent as the felt material.

The semi-solid lubricating medium tends, in addition to its lubricating functions, to add a body to the felt material, strengthening and stiffening the same sufficiently to support it 95 against free resiliency when it is in contact with the cylinder wall surface, all without interfering with the ability of the impregnated guide felt to wear away at substantially the same rate as the grinding stone or other abrasive element.

We have also found that effects similar to the foregoing may be accomplished by impregnating the felt, or similar, material with a medium consisting of a mixture of linseed oil, benzine and graphite. The linseed oil 100 has a tendency to set when cold and has a sufficiently heavy body to tend to prevent "throwoff" of the same during movement of the tool in the cylinder. The graphite adds lubricating qualities, as in the previous instances, and the benzine serves as a cutting agent for thinning the linseed oil sufficiently for it to readily penetrate the felt material. The benzine quickly evaporates and leaves the 105 linseed oil base in the felt material in its original condition. In this instance heating of the linseed oil is not necessary as will be 110 well appreciated.

The advantages of our invention will be 115 obvious from the foregoing. The grinding 120

operation is of a dry grinding character with the attendant fast cutting feature. The lubricant-impregnated guides apply to the cylinder wall surface a very thin film of the lubricating medium which picks up the abrasion dust from the cylinder-wall surface and loads and weights the same so that it is not thrown about promiscuously as free dry dust. There is no formation of a fluid or abrasive soup.

10 The lubricant-gathered abrasion dust, which takes a somewhat greasy, lumpy or crumble form, falls directly down through the cylinder bore where it may be readily caught in any desired manner without the danger of the same getting upon surrounding parts or mechanism. The operator may do his work efficiently without danger of injury to his lungs. This arrangement provides for cleanliness. The surrounding environment is not covered with dust as in prior cases of dry grinding. The objectionable smearing of abrasive soup is eliminated. The operator can employ his entire time in the manipulation of the tool in the cylinder and does not have to bear in mind proper lubrication. These advantages are attained without affecting the ability of the tool to cut uniformly, smoothly and rapidly. Efficiency of the tool is considerably increased. The cost of operation of the tool as well as the ultimate cost of the cylinder grinding operation to the customer is materially reduced. A tool is provided which is light in weight and easy to handle and which is capable of use over long periods of time with less than the customary wear in tools of this character. Heretofore, in attempts to get away from the difficulties experienced in the use of prior methods, there have been developed and marketed receptacles for catching abrasive "soup" and suction or vacuum devices for carrying off free abrasive dust. These, however, add materially to the cost of equipment. Our invention eliminates such devices with material saving in time, cost and investment.

Various changes in the foregoing details and arrangements of parts and treatments may be made without departing from the spirit and scope of our invention as defined by the claims which follow.

We claim:

1. In a tool of the character described, a body, abrading elements and non-abrasive guide elements carried by said body and adapted to engage the cylinder wall surface, said guide elements being formed of a material which wears away at a rate substantially as fast as said abrasive elements, and means for adjusting all of said elements simultaneously toward and from the cylinder wall surface, said guide elements being treated with a lubricating medium of a character which assumes a semi-hardened state when cooled, cylinder grinding lubrication being effected solely thereby.

2. In a cylinder grinding tool, a frame, supporting adjustable portions adapted to engage the cylinder wall surface for guiding-abrading purposes, certain of said portions being non-abrasive in character and impregnated with a lubricating medium which is applied to the cylinder wall surface by contact of said portions with such wall surface, and the remainder of said portions being abrasive in character. 70

3. In a cylinder grinding tool, a frame supporting adjustable portions adapted to engage the cylinder wall surface for guiding-abrading purposes, certain of said portions being formed of a fibrous material impregnated with a lubricating medium which is applied to the cylinder wall surface by contact of said fibrous material portions with such wall surface. 80

4. In a cylinder grinding tool, a frame supporting adjustable portions adapted to engage the cylinder wall surface for guiding-abrading purposes, certain of said portions being formed of a non-abrasive felt material impregnated with a lubricating medium which in its cooled state assumes a semi-solid condition and which is applied to the cylinder wall surface by contact of said felt material portions with such wall surface. 85

5. In a tool of the character described, a frame, abrading elements supported by said frame, lubricating guide elements supported by said frame, said latter elements being non-abrasive and having the ability to wear away substantially as fast as said abrasive elements, 95 and means for adjusting said elements into contact with the cylinder wall surface. 100

6. In a tool of the character described, a frame, abrading elements supported by said frame, lubricating guide elements supported by said frame, said latter elements having their cylinder contacting surface formed of a felt, or similar, material impregnated with a lubricating medium which assumes a semi-solid state when cool, and means for adjusting said elements into contact with the cylinder wall surface. 110

7. In a tool of the character described, a frame, abrading elements supported by said frame, lubricating guide elements supported by said frame, and means for simultaneously adjusting said elements to similar extents into contact with the cylinder wall surface, said guide elements being formed of a felt, or similar, material having the ability to wear 115 at substantially the same rate as the abrasive elements. 120

8. In a tool of the class described, a frame, carrier members supported by said frame, abrading elements supported by certain of said carrier members, means for adjusting said carrier members to bring said abrading elements into contact with the cylinder wall surface, and guide elements carried by other of said carrier members and impregnated 125 130

with a lubricant for lubricating the cylinder wall surface being ground.

9. In a tool of the character described, a frame, abrading elements supported by said frame, means for adjusting said elements into contact with the cylinder wall surface, and means carried by said frame for lubricating the cylinder wall surface being ground, said lubricating means also serving to guide and

10 partially support the tool in the cylinder.

10. In a tool of the character described, a frame, abrading elements supported by said frame, means for adjusting said elements into contact with the cylinder wall surface, and lubricant-impregnated felt, or similar, material carried by said frame and engaging the cylinder wall for lubricating the cylinder wall surface being ground.

11. In a tool of the character described, 20 a frame, abrading elements supported by said frame, means for adjusting said elements into contact with the cylinder wall surface, and lubricant-impregnated felt, or similar, material carried by said frame and engaging 25 the cylinder wall for lubricating the cylinder wall surface being ground, and means for supporting said felt in contact with the cylinder wall to aid in guiding and supporting the tool in the cylinder.

30 12. In a tool of the character described, a plurality of carriers adjustable to expand and contract the working diameter of the tool, abrading elements supported by certain of said carriers, and non-abrasive guide 35 elements supported by the other of said carriers, all said elements being adapted to engage the cylinder wall surface, said guide elements being formed of a felt, or like, material impregnated with a lubricant medium.

40 13. In a tool of the character described, a plurality of carriers adjustable to expand and contract the working diameter of the tool abrading elements supported by certain of said carriers, and non-abrasive guide elements supported by the other of said carriers, all said elements being adapted to engage the cylinder wall surface, said guide elements being formed of a felt, or like, material impregnated with a lubricant medium, 50 which when cool assumes a semi-solid condition so as to not be thrown off from said guides during the movement of the tool and which when converted to fluid form readily penetrates and saturates the felt material.

55 14. In a tool of the character described, a plurality of carriers adjustable to expand and contract the working diameter of the tool, abrading elements supported by certain of said carriers, and guide elements supported by other of said carriers, all said elements being adapted to engage the cylinder wall surface, said guide elements being formed of a felt, or like, material which has the ability to wear away substantially at the same 65 rate as said abrasive elements, said felt ma-

terial being impregnated with a semi-solid lubricating medium to serve as the sole grinding lubricating agent notwithstanding wear of the felt, said medium also serving to stiffen the felt material to oppose free resiliency

70

15. In a tool of the character described, an abrading element engageable with the cylinder wall surface, and a guide element of a non-abrasive character cooperating with the abrasive element to position the tool in the cylinder, said guide element being saturated with a lubricant which is applied to the surface being treated by the grinding motion of the tool and under the influence of heat developed by friction between said guide element and said surface.

80

16. In a tool of the character described, an abrading element engageable with the cylinder wall surface, and a self-lubricating guide element cooperating with the abrasive element to position the tool in the cylinder, said guide element being formed of felt, or similar, material which has the ability to wear at substantially the same rate as the abrasive element and said felt material being impregnated with a lubricating medium semi-solid in its normal condition for effecting grinding lubrication and for preventing release of free grinding dust.

85

17. In a tool of the class described, a plurality of abrasive members adapted to engage the surface to be dressed, and a plurality of lubricant-impregnated guide elements adapted to engage the surface to be treated ahead of said abrasive elements and to deposit a film of lubricant on the surface to be dressed before abrasion takes place to prevent free release of abrasion dust.

90

18. In a tool of the class described, a frame, a plurality of abrasive members carried thereby and adapted to engage the surface to be dressed, a plurality of lubricant-impregnated guide elements carried by said frame and adapted to engage the surface to be treated ahead of said abrasive elements and to deposit a film of lubricant on the surface to be dressed before abrasion takes place, and means for simultaneously adjusting all said elements to similar extents.

100

19. In combination in a tool of the class described, an abrasive cylinder wall contacting portion and a non-abrasive cylinder wall contacting portion which takes the form of a piece of felt material impregnated with a semi-solid lubricating medium, both said portions being adjustable to vary the working size of the tool.

110

20. In combination in a tool of the class described, an abrasive cylinder wall contacting portion and a non-abrasive cylinder wall contacting portion which takes the form of a piece of felt material impregnated with a lubricating medium including tallow, or the

120

125

130

like material, and means for adjusting said portions to expand and contract the tool.

21. In combination in a tool of the class described, an abrasive cylinder wall contacting portion, and a non-abrasive cylinder wall contacting portion which takes the form of a piece of felt material impregnated with a lubricating medium including tallow, or like material and graphite and frame means 10 adjustably supporting both said portions.

22. In combination in a tool of the class described, an abrasive cylinder wall contacting portion, and a non-abrasive cylinder wall contacting portion which takes the form of 15 a piece of felt material impregnated with a lubricating medium including tallow and graphite, the quantity of said graphite used being substantially that which said tallow will hold in suspension in a heated and fluid 20 condition, and frame means adjustably supporting both said portions.

23. In combination in a tool of the class described, an abrasive cylinder wall contacting portion and a non-abrasive cylinder wall 25 contacting portion which takes the form of a piece of felt material impregnated with a lubricating medium including linseed oil and graphite.

24. In combination in a tool of the class 30 described, an abrasive cylinder wall contacting portion and a non-abrasive cylinder wall contacting portion which takes the form of a piece of felt material treated with a lubricating medium including linseed oil, benzine and 35 graphite.

25. In combination in a tool of the class described, an abrasive, lubricant-impregnated cylinder wall contacting portion, a non-abrasive cylinder wall contacting portion 40 which takes the form of a piece of felt material impregnated with a semi-solid lubricated medium, and means for adjustably supporting both said portions for expansion and contraction movements.

45. 26. A cylinder wall contacting guide for a cylinder grinding tool which comprises a body portion adapted for adjustable support in the tool and a non-abrasive cylinder wall contacting element carried by said body and 50 formed of fibrous material of a normally compressible nature, said material being impregnated with a semi-solid lubricant stiffening and strengthening the same against compression forces and for applying a film of 55 lubricating medium to the cylinder wall surface by directly contacting and passing over the latter.

27. A wall-contacting unit for a tool of the class described which comprises a supporting member having a channel in its outer surface adjacent the wall surface to be treated, and a non-abrasive element secured in 60 said channel and projecting therefrom for engagement with the wall surface to be treated, said element being formed of a fibrous 65

material impregnated with a lubricant which is applied to the wall surface by the operating contact of said element therewith.

28. A wall-contacting unit for a tool of the class described which comprises a supporting member having a channel in its outer surface adjacent the wall surface to be treated, and a non-abrasive element secured in 70 said channel and projecting therefrom for engagement with the wall surface to be treated, said element being formed of comparatively rigid felt material having the ability to wear away substantially as fast as an abrasive material. 75

29. A removable and replaceable wall-contacting unit for a tool of the class described which comprises a relatively stiff metallic supporting member having an elongated channel therein which opens outwardly toward the wall surface to be treated, and a 80 non-abrasive element fixedly secured in and extending substantially throughout the length of said channel and projecting from the open side thereof for engagement with the surface to be treated, said element being 85 formed of a felt material impregnated with a semi-solid lubricating medium. 90

30. An adjustable unit for a tool of the class described which comprises an elongated carrier member having a channel in its outer 95 edge surface, its inner edge being adapted for operative connection to expanding means, a rigid channeled member mounted in the channel of said carrier member, and a wall-contacting element mounted in the channel of 100 said channeled member and having a part projected for engagement with the wall surface to be treated, said element being formed of a fibrous non-abrasive material impregnated with a lubricating medium and which is 105 of a character having the ability to wear away substantially at the rate of an abrasive material. 110

31. In a tool of the character described, a plurality of carriers adjustable to expand 115 and contract the tool to different diameters, abrading elements carried by certain of said carriers and non-abrasive guide elements carried by other of said carriers, all said elements being adapted to engage the cylinder 120 wall surface, said guide elements being formed of felt material treated with a stiffening material to give said elements a sufficiently rigid body to prevent collapsing of the same under grinding pressure contact. 125

32. In a tool of the character described, a plurality of carriers adjustable to expand and contract the tool to different diameters, abrading elements carried by certain of said carriers and non-abrasive guide elements carried by other of said carriers, all said elements being adapted to engage the cylinder wall surface, said guide elements being formed of medium-hard felt material treated with a stiffening agent to give said elements 130

a sufficiently rigid body to prevent collapsing of the same under grinding pressure contact and to provide a carrier-guide-surface which will wear away substantially the same as the
5 said abrading elements.

In witness whereof, we have subscribed our names.

FREDERICK G. WACKER.
